ENGINE OR MOTOR.

1,392,322.

Specification of Letters Patent.

Patented Oct. 4, 1921.

Application filed August 11, 1919. Serial No. 316,821.

To whom it may concern:

Be it known that I, GEORGE W. GILL, a citizen of the United States, residing at Battle Creek, county of Calhoun, State of Michigan, have invented certain new and useful Improvements in Engines or Motors, of which the following is a specification.

This invention relates to improvements in engines or motors.

10 My improved engine or motor is especially designed by me for ringing the bell of a locomotive although it is readily adapted and desirable for use in other relations.

I have illustrated my improvements as I 15 have embodied them as a bell ringing motor.

The main objects of this invention are:

First, to provide an improved motor or engine for ringing the bell of a locomotive, which imparts a full stroke to the bell but 20 does not permit it to revolve or "hang up."

Second, to provide an improved motor or engine having these advantages which is comparatively simple and economical in structure and very durable in use, and one 25 which is not likely to get out of repair or become inoperative.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment of my invention is clearly illustrated 35 in the accompanying drawing forming a part of this specification, in which:

Figure I is a side elevation of a structure embodying the features of my invention, 40 same being shown mounted upon a locomotive which is shown in section on a line corresponding to line 1—1 of Fig. II.

Fig. II is a detail side elevation looking from the right of Fig. I, the movement of 45 certain parts being indicated by dotted lines.

Fig. III is an enlarged detail view partially in vertical section on a line corresponding to line 3—3 of Figs. V and VI, the exhaust valve carried by the piston being 50 shown in its seated position, the piston being at the inner end of its stroke.

Fig. IV is a similar detail view partially in section on a line corresponding to line 4—4 of Fig. II, the inlet valve being seated

and the exhaust valve carried by the piston 55 being open, the piston being at the outer end of its stroke.

Fig. V is a detail view partially in section on a line corresponding to line 5—5 of Fig. III.

Fig. VI is a detail section on a line corresponding to line 6—6 of Figs. I and III.

Referring to the drawing, 1 represents the body of a locomotive, 2 a bell, and 3 its supporting standard. The bell is carried by 65 the crank 4, having an arm 5 at one end adapted to be operated by means of a rope or the like. At its other end the crank 4 has an arm 6 provided with a wrist pin 7. These parts have been shown conventionally as 70 their structure is well-known.

My improved engine or motor comprises a cylinder 8 having heads 9 and 10 which, in the structure illustrated, are threaded 75 thereon. A gasket disk 11 is provided for the outer head 9. The inner head 10 is secured upon the bracket 12 by means of screws 12', thereby supporting the cylinder in an upright position. The cylinder is provided with side ports 13 and 14 spaced from 80 its ends, the lower end of the cylinder constituting a work chamber and the upper end a dash pot chamber. I have used the terms "upper" and "lower" mainly for convenience in description. Between the ports 13 and 14, 85 the cylinder has longitudinal slots 15.

The piston 16 carries a piston pin 17 engaging the pitman yoke 18 which is arranged to embrace the upper end of the piston. The pitman 19 has a slide 20 mounted thereon for limited sliding movement, the wrist pin 7 being engaged with this slide, the purpose of this slide connection being to allow the bell to swing under the impulses 90 of the engine.

In the inner end of the piston is a tubular valve casing 21 having a seat 22 therein for the plunger valve 23. The valve casing has a relief port 24 in its outer end communicating with the annular groove 25 of 100 the piston pin 17 which has a series of longitudinal grooves 26 therein communicating with this annular groove 25 thereby providing delivery passages for the relief valve 23. The relief passages 27 are disposed 105 diagonally of the piston and open into the valve casing 21 at the inner side of the valve seat. An inlet valve casing designated gen-

erally by the numeral 28 is threaded into the head 10 of the cylinder centrally below the valve 23, the inlet valve casing being connected by the pipe 29 to a source of supply such as compressed air or steam. The inlet valve 30 is adapted to seat upwardly against the seat 31, and projects into the work chamber of the cylinder in alinement with the valve 23, so that on the return stroke of the piston the inlet valve is unseated or opened. The screw 32 supports the valve in its open position and provides an adjusting means for timing the valve.

To guide and support the pitman yoke, I mount a sleeve 33 upon the cylinder and slides 34 in the longitudinal slots of the cylinder to be engaged by the pin 17. With the parts thus arranged, the operation of the device is as follows:

With the parts in their initial position as shown in Fig. III, except that the valve 23 is there shown closed, on the admission of motive fluid, valve 23 is first automatically closed by the action of the fluid, the piston then being subject to the action of the fluid is actuated and the inlet valve 30 is automatically seated or closed, which, however, does not take place until a full charge of the motive fluid is admitted to the cylinder. When the piston uncovers the exhaust ports 13, the cylinder exhausts therethrough, and owing to the chamber then being open to the atmosphere, the sustaining pressure on the relief valve is removed and the valve becomes unseated or opens and drops upon the valve 30.

The energy of the motive fluid and the impetus of the bell carries the piston upwardly closing the port 14 and the upper end of the piston acts as a dash pot to check the piston. The lost motion connection between the pitman and the bell described permits a full stroke of the bell but prevents its turning over completely. The weight of the bell and the reaction on the piston of the dash pot returns the piston to its normal or initial position and unseats the inlet valve which again admits the motive fluid and the operation is repeated.

My improved bell ringing device is simple and economical in its parts, and is very durable and not likely to get out of repair.

I have illustrated and described my invention in the form in which I have embodied the same in practice. I have not attempted to illustrate or describe other modifications and adaptations as I believe the disclosure made will enable those skilled in the art to which my invention relates to embody or adapt the same as may be desired.

Having thus described my invention, what I claim as new and desire to secure by Letters Patent is:

1. In a structure of the class described, the combination of a cylinder having side

ports spaced from its ends, one end of said cylinder constituting a work and the other a dash pot chamber, said cylinder being longitudinally slotted between its said ports, a piston, the outer end of which constitutes a dash pot member, a tubular piston relief valve casing disposed centrally and longitudinally of said piston and having a discharge port at its outer end and a relief passage opening through the side thereof, a plunger piston valve disposed in said casing to seat outwardly therein, a piston pin having a longitudinal passage communicating with the discharge port of said piston valve casing, an inlet valve casing communicating with the inner end of said cylinder, a plunger inlet valve projecting into said cylinder to be engaged by said piston valve on the return stroke of said piston whereby said inlet valve is unseated, a sleeve slidably on said cylinder, slides disposed within said sleeve coacting with said slots of said cylinder, and a pitman yoke engaging said piston pin.

2. In a structure of the class described, the combination of a cylinder having side ports spaced from its ends, one end of said cylinder constituting a work and the other a dash pot chamber, a piston, the outer end of which constitutes a dash pot member, a tubular piston relief valve casing disposed centrally and longitudinally of said piston and having a discharge port at its outer end and a relief passage opening through the side thereof, a plunger piston valve disposed in said casing to seat outwardly therein, an inlet valve casing communicating with the inner end of said cylinder, and a plunger inlet valve projecting into said cylinder to be engaged by said piston valve on the return stroke of said piston whereby said inlet valve is unseated.

3. In a structure of the class described, the combination of a cylinder having a side exhaust port, said cylinder being longitudinally slotted, a piston, a tubular piston relief valve casing disposed centrally and longitudinally of said piston and having a discharge port at its outer end and a relief passage opening through the side thereof, a plunger piston valve disposed in said casing to seat outwardly therein, a piston pin having a longitudinal passage communicating with the discharge port of said piston valve casing, an inlet valve casing communicating with the inner end of said cylinder, a plunger inlet valve projecting into said cylinder to be engaged by said piston valve on the return stroke of said piston whereby said inlet valve is unseated, a sleeve slidably on said cylinder, slides disposed within said sleeve coacting with said slots of said cylinder, and a pitman yoke engaging said piston pin.

4. In a structure of the class described,

- the combination of a cylinder having a side exhaust port, a piston, a tubular piston relief valve casing disposed centrally and longitudinally of said piston and having a discharge port at its outer end and a passage opening through the side thereof, a plunger piston valve disposed in said casing to seat outwardly therein, an inlet valve casing communicating with the inner end of said cylinder, and a plunger inlet valve projecting into said cylinder to be engaged by said piston valve on the return stroke of said piston whereby said inlet valve is unseated. 5

5. In a structure of the class described, the combination of a cylinder having side ports spaced from its ends, one end of said cylinder constituting a work and the other a dash pot chamber, said cylinder being longitudinally slotted between its said ports, 10 a piston, the outer end of which constitutes a dash pot member, an outwardly seating relief valve, a piston pin, a reciprocating automatically seating inlet valve projecting into said cylinder to be engaged by said relief valve on the return stroke of said piston whereby said inlet valve is unseated, a sleeve 15 slidable on said cylinder, slides disposed within said sleeve coacting with said slots of said cylinder, and a pitman yoke engaging said piston pin. 20

6. In a structure of the class described, the combination of a cylinder having side ports spaced from its ends, one end of said cylinder constituting a work and the other a dash pot chamber, a piston, the outer end of which constitutes a dash pot member, a relief valve carried by said piston, a reciprocating automatically seating inlet valve projecting into said cylinder to be engaged by 25 said relief valve on the return stroke of said piston whereby said inlet valve is unseated, a sleeve slidable on said cylinder, slides disposed within said sleeve coacting with said slots of said cylinder, and a pitman yoke engaging said piston pin. 30

7. In a structure of the class described, the combination of a cylinder having side ports spaced from its ends, one end of said cylinder constituting a work and the other a dash pot chamber, said cylinder being longitudinally slotted between its said ports, a piston, the outer end of which constitutes a dash pot member, a relief valve carried by 35 said piston, a reciprocating automatically seating inlet valve projecting into said cylinder to be engaged by said relief valve on the return stroke of said piston whereby said inlet valve is unseated, a sleeve slidable on said cylinder, slides disposed within said sleeve coacting with said slots of said cylinder, and a pitman yoke engaging said piston pin. 40

8. In a structure of the class described, the combination of a cylinder having an exhaust port spaced from its end, said cylinder being longitudinally slotted between its said ports, a piston, an outwardly seating relief valve carried by said piston, a piston pin, a reciprocating automatically seating inlet valve projecting into said cylinder to be engaged by said piston valve on the return stroke of said piston whereby said inlet valve is unseated. 45

9. In a structure of the class described, the combination of a cylinder having an exhaust port spaced from its end, a piston, an outwardly seating relief valve carried by said piston, and a reciprocating automatically seating inlet valve projecting into said cylinder to be engaged by said piston valve on the return stroke of said piston whereby 50 said inlet valve is unseated. 55

10. In a structure of the class described, the combination of a cylinder having an exhaust port spaced from its end, a piston, an outwardly seating relief valve carried by said piston, a reciprocating automatically seating inlet valve operatively associated with said piston so that on the return stroke of said piston said inlet valve is unseated, and a timing means for said inlet valve. 60

11. In a structure of the class described, the combination of a cylinder having an exhaust port spaced from its end, a piston, an outwardly seating relief valve carried by said piston, and a reciprocating automatically seating inlet valve operatively associated with said piston so that on the return stroke of said piston said inlet valve is unseated. 65

In witness whereof, I have hereunto set my hand and seal in the presence of two witnesses.

GEORGE W. GILL. [L.S.]
